G. H. TOMLINSON.

APPARATUS FOR TREATING LIGNO CELLULOSE FOR RECOVERING TURPENTINE AND SUGAR.
APPLICATION FILED DEC. 20, 1910.

1,032,444.

Patented July 16, 1912.

UNITED STATES PATENT OFFICE.

GEORGE H. TOMLINSON, OF CHICAGO, ILLINOIS, ASSIGNOR TO STANDARD ALCOHOL COMPANY, OF NEW YORK, N. Y., A CORPORATION OF MAINE.

APPARATUS FOR TREATING LIGNOCELLULOSE FOR RECOVERING TURPENTINE AND SUGAR.

1,032,444.

Specification of Letters Patent. Patented July 16, 1912.

Application filed December 20, 1910. Serial No. 598,299.

To all whom it may concern:

Be it known that I, GEORGE H. TOMLINSON, a subject of the King of England, residing at Chicago, in the county of Cook and State of Illinois, have invented a certain new and useful Improvement in Apparatus for Treating Lignocellulose for Recovering Turpentine and Sugar, of which the following is a specification.

10 My invention relates to improvements in means for treating ligno-cellulose for the recovery of turpentine and fermentable sugar, and is illustrated in one form in the accompanying drawing which shows a dia-grammatic elevation in part section.

The digester A which is rotatably mounted on the trunnions A² in the bearings A², is driven by the worm A³ and wheel A⁴ and contains the axially located perforated pipe A⁵ which is closed at one end by the blind flange A⁶, passes out of the digester through the stuffing box A⁷ and communicates by means of the pipe A⁸ and supply valve A⁹ with any suitable source of steam supply not shown. The pressure gage A¹⁰ is connected by means of the pipe A¹¹ with the pipe A⁵. The pipe B which is closed at one end by the blind flange A⁶ has the upwardly extending perforated branch B¹ within the 30 digester and connects at its outer end with the pipe B² which is controlled by the exhaust valve B³ and leads to the condenser B⁴. The by-pass B⁵ controlled by the safety pop valve B⁶ leads from the pipe B² on one 35 side of the valve B³ back to the pipe on the other side. Water is supplied to the condenser by the pipe C controlled by the valve C¹ and discharged therefrom by the pipe C². The condensation products are discharged 40 from the condenser through the pipe C³ to the separator C⁴ which extracts the turpentine. The sawdust or ligno-cellulose which is to be used is stored in the bin or hopper D and discharged therefrom into the digester through the man-hole D¹, being controlled by the valve D².

It will be evident that while I have shown in my drawing an operative device still many changes might be made in size, shape 50 and arrangement of the parts without departing materially from the spirit of my invention, and I wish, therefore that my drawing be regarded as in a sense diagrammatic.

The use and operation of my invention are 55 as follows:—In using my apparatus the digester is charged with finely comminuted ligno-cellulose such as saw dust which may be acidulated either before or after being placed therein. The man-hole is closed, and 60 steam is allowed to enter, displacing the air which passes out through the exhaust valve. The entrance of steam continues after the complete expulsion of air, and as the temperature rises hydrocarbon vapor passes off 65 with some of the steam to the condenser where it is condensed and discharged in the form of a liquid made up of water and the hydrocarbon. From this fluid, the hydrocarbon is separated out in any one of the 70 usual manners. After the digester and its contents have been thoroughly heated by the free steam, the discharge valve is closed and the pressure and temperature in the digester allowed to rise, being controlled by the pop 7 safety valve, until the point desired for the conversion of wood to sugar has been reached. This temperature and pressure is held for the correct time and the digester is then allowed to exhaust into the condenser, 75 and the remainder of the hydrocarbon is there recovered. In case sulfuric acid is used as the hydrolyzing agent, the turpentine may undergo partial or complete conversion to cymene or analogous hydrocarbons. The mass left in the digester is then 80 removed therefrom and prepared for treatment in the diffusion battery where it is treated for the recovery of the sugar which has been converted by the above described 85 treatment with steam in the digester.

It will be evident that this apparatus may be used for the recovery of turpentine only when coniferous or turpentine-containing woods are being treated in the digester. 90

I claim:

1. Apparatus for treating ligno-cellulose or the like, comprising a digester, means for introducing steam thereinto and withdrawing vapor therefrom, a condenser for volatile products, a valved conduit between said digester and condenser, a by-pass around said valve and a relief valve in said by-pass. 100
2. Apparatus for treating ligno-cellulose or the like, comprising a digester mounted for rotation, means for introducing steam thereinto and withdrawing vapors therefrom without interrupting its rotation, a 105

condenser for volatile products, a valved conduit between said digester and condenser, a by-pass around said valve and a relief valve in said by-pass.

- 5 3. Apparatus for treating ligno-cellulose or the like, comprising a digester mounted for rotation, a fixed pipe or conduit extending axially therethrough and having non-communicating perforate and imperforate

sections, a steam-supply connection to the perforate section, and an eduction pipe extending into the vapor-space of the digester and communicating with the imperforate section.

GEORGE H. TOMLINSON.
